UNITED STATES PATENT OFFICE.

REGINA PARENT GRIFFIN, OF GRAND FORKS, NORTH DAKOTA, ASSIGNOR OF ONE-HALF TO GEORGE S. KOFFEND, OF MINNEAPOLIS, MINNESOTA.

REVERSIBLE CUFF FOR SHIRTS.

Application filed August 22, 1919. Serial No. 319,097.

To all whom it may concern:

Be it known that I, REGINA PARENT GRIFFIN, a citizen of the United States, residing at Grand Forks, in the county of 5 Grand Forks and State of North Dakota, have invented certain new and useful Improvements in Reversible Cuffs for Shirts; and I do hereby declare the following to be a full, clear, and exact description of the invention, such as will enable others skilled in the art to which it appertains to make and 10 use the same.

My invention has for its object to provide an extremely simple and highly efficient reversible shirt cuff; and to such ends, generally stated, the invention consists of the novel construction and combination of parts hereinafter described and defined in the 15 claims.

20 Particularly, this invention relates to soft cuffs that are adapted to be folded to form what is usually designated as a "French cuff." For carrying out my invention, I preferably provide the shirt sleeves with 25 main cuffs made substantially like the ordinary "French cuff," but in addition thereto, I provide a supplemental cuff which is attached to the main cuff at its ends, but is loose at both edges, so that the two-flap cuff 30 thus formed may be turned inside out. Button holes are provided, both in the main and supplemental cuffs, both above and below the peripheral folding line. With this arrangement, the cuff structure can be turned 35 either side out, that is, so that the supplemental cuff will come, either on the inside or on the outside of the main cuff, and in either of such adjustments, the cuff can then be folded outward on its folding line to afford 40 the French cuff formation. These two adjustments bring different surfaces of the main and supplemental cuffs to exposed positions, and in both adjustments, the folds 45 of the cuff will be turned outward, so as to give the proper appearance to the cuff.

The improved cuff is illustrated in the accompanying drawings wherein like characters indicate like parts throughout the several views.

50 Referring to the drawings:

Fig. 1 is a perspective view showing the cuff before it is folded to form the French cuff, but with the supplemental cuff on the outer side of the main cuff;

Fig. 2 is an enlarged section in perspective taken on the line 2—2 of Fig. 1; 55

Fig. 3 is a perspective view showing the cuff first adjusted, as shown in Fig. 1 and then folded on the folding line y to form the French cuff; 60

Fig. 4 is a section in perspective on the line 4—4 of Fig. 3;

Fig. 5 is a perspective view of the cuff showing the same immediately after it has been turned inside out, in respect to Fig. 1; 65

Fig. 6 is a view corresponding to Fig. 5 but showing the supplemental cuff pressed back within the main cuff;

Fig. 7 is a view corresponding to Fig. 3 but showing the cuff folded on the line y — y 70 to form the French cuff after the supplemental cuff has been turned within the main cuff, as shown in Fig. 6; and

Fig. 8 is a section in perspective taken on the line 8—8 of Fig. 7. 75

The shirt sleeve is indicated by the numeral 9 and the main cuff, which at its lower or inner edge is stitched thereto in the customary way, is indicated by the numeral 10. This main cuff and the supplemental cuff are 80 preferably, and, as shown, each formed twoply with their edges finished by what is known as "French seams." The supplemental cuff 11, at its ends, is stitched to the ends of the main cuff, as indicated at 12, but 85 both longitudinal edges of the said supplemental cuff are loose, and these loose longitudinal edges being stitched, preferably, by French seams. Both the main and supplemental cuffs are preferably of the same 90 width. The main cuff, inward of the folding line y , has the customary button holes 13 and outward of the said folding line has the customary button holes 14. The supplemental cuff 11, in line with button holes 13, 95 is provided with button holes 15, and in line with button holes 14, is provided with button holes 16. This arrangement of the button holes of the main and supplemental cuffs is such that, in the different adjustments of the cuff shown in Figs. 3 and 7, all of the button holes 13, 14, 15 and 16, will be brought into proper alignment for the insertion of the cuff buttons. 100

When the cuff is turned, as shown in Fig. 1, the supplemental cuff will be at the outer side of the cuff, thereby exposing the surface A of said supplemental cuff at the outer

side of the cuff and surface B of the main cuff at the inner side of the cuff. When this cuff is then folded, as shown in Fig. 3, surfaces A of the supplemental cuff will be 5 turned together and surfaces B of the main cuff will be exposed, both at the outer and inner side of the cuff.

When the cuff is turned, as shown in Fig. 6, surfaces B of the main cuff will be at the 10 outer side of the cuff, but when the cuff is then folded, as shown in Fig. 7, surface A of the supplemental cuff will be exposed, both at the inner and outer portions of the cuff.

Obviously, these two arrangements expose 15 different surfaces of the composite cuff so that when surface B of main cuff is soiled, clean surface A of supplemental cuff may be then turned outward and exposed. Of course, the reverse of the above statement is 20 also true.

This cuff is especially designed for use as a French cuff, but if a simpler form of cuff is desired, the main and supplemental cuffs might be made narrower and would not need 25 to be folded, but will, nevertheless, be turned inside out, or reversed, to give the several clean surfaces.

The cuff above described, is not only simple and easy to make, but its edges may be 30 properly finished and the cuff is easily re-

versible. Moreover, in all of the adjustments, properly finished surfaces are always provided at the outer side of the cuff, so that in no case, does the cuff have the appearance of having been turned inside out. 35

What I claim is:

1. A shirt sleeve having a main cuff attached thereto at one longitudinal edge, and a supplemental cuff attached to the end edges of said main cuff at its end edges but 40 free at both longitudinal edges, said main and supplemental cuffs being of approximately the same width.

2. A shirt sleeve having a main cuff attached thereto at one longitudinal edge, a 45 supplemental cuff attached to the end edges of said main cuff at its end edges but free at both longitudinal edges whereby the complete cuff may be turned either side out, the said main and supplemental cuffs having a 50 central folding line and having alignable button holes on opposite sides of such folding line, thereby affording a reversible French cuff.

In testimony whereof I affix my signature 55 in presence of two witnesses:

REGINA PARENT GRIFFIN.

Witnesses:

WINIFRED I. WARD,

HARRY D. KILGORE.
